UNITED STATES PATENT OFFICE.

WILLIAM HEEREN, OF PITTSBURG, PENNSYLVANIA.

DESIGN FOR A BADGE OR SIMILAR ARTICLE.

SPECIFICATION forming part of Design No. 29,864, dated December 27, 1898.

Application filed August 1, 1898. Serial No. 687,378. Term of patent 7 years.

To all whom it may concern:

Be it known that I, WILLIAM HEEREN, a citizen of the United States of America, residing at Pittsburgh, in the county of Allegheny and

5 State of Pennsylvania, have invented a certain new and useful Design for a Badge or Similar Article, of which the following is a specification, reference being had therein to the accompanying drawings.

10 My design consists of a badge or similar article comprising an oblong body 1, which is somewhat tapered toward one end, and is superimposed upon a background 3, which in its general outline resembles a leaf.

15 The oblong body 1 has formed thereon surface warts or projections 2, which are irregularly disposed throughout its length.

In the accompanying drawings my design is shown in plan view in Figure 1, and in Fig. 2 is shown a cross-sectional view on the line 20 *xx* of Fig. 1.

Having described my invention, what I claim as new, and desire to secure by Letters Patent, is—

The design for a badge or similar article as 25 herein shown and described.

In testimony whereof I affix my signature in the presence of two witnesses.

WILLIAM HEEREN.
